UNITED STATES PATENT OFFICE.

CHARLES H. LISTER, OF ST. PAUL, MINNESOTA, ASSIGNOR TO MINNESOTA MANUFACTURERS ASSOCIATION, OF MINNEAPOLIS, MINNESOTA, A CORPORATION OF MINNESOTA.

AUTOMATIC LOADER FOR LIFT-CARRIERS.

1,021,876.

Specification of Letters Patent.

Patented Apr. 2, 1912.

Application filed May 23, 1910. Serial No. 562,903.

To all whom it may concern:

Be it known that I, CHARLES H. LISTER, a citizen of the United States, residing at St. Paul, in the county of Ramsey and State of Minnesota, have invented certain new and useful Improvements in Automatic Loaders for Lift-Carriers, of which the following is a specification.

My invention relates to improvements in automatic loaders for lift carriers, its object being to provide improved means for automatically regulating and facilitating the transfer of packages from an inclined carrier to a vertical or straight lift elevator.

Where a succession of packages are run down an inclined carrier to be picked up by a straight lift elevator, some means must be provided for checking the travel of the succeeding packages until the foremost package has been picked up by the elevator and carried to a different level. But when the carrier is inclined very slightly or not at all at its discharge end, and the run of the succeeding packages has thus been checked, it is necessary that some means be provided for again setting them in motion and projecting them onto the elevator. With these objects in view I have provided improved means controlled by the travel of the elevator for automatically regulating and facilitating the loading of the packages in a step by step manner from an inclined carrier to the loading platform of a straight lift elevator.

To this end the invention consists in the construction, combination and arrangement of parts hereinafter described and claimed.

In the accompanying drawings forming part of this specification, Figure 1 is a perspective view of a carrier embodying the invention with some parts broken away; Fig. 2 is a detail in perspective of one of the elevator platforms; Fig. 3 is a longitudinal section on line $\alpha-\alpha$ of Fig. 1, with some parts broken away, showing the parts in box-arresting position; Fig. 4 is a similar view showing the parts in box-discharging position; and Figs. 5, 6, 7 and 8 are diagrammatic views of the straight lift elevator and the discharge end of the inclined carrier showing the parts in several successive positions assumed by them in the operation of the elevator.

In the embodiment of the invention shown in the drawings A represents the frame of

one of the loading platforms of a straight lift elevator of a type well known in the art, and B the side bars of an inclined gravity carrier, also of a type well known in the art, which is almost horizontal at its discharge end. In these side bars are journaled the rollers C of the carrier. The side members of the loading platform are secured by means of bolts 2 upon the vertical guides D of the elevator frame. For convenience and clearness of illustration I have shown the guides on one side only of the elevator frame. Within these guides works an elevator of well known construction having a series of horizontal platforms or trays E supported one above another at convenient and equal distances apart. Each platform consists of a cross bar 3, which fits slidingly within the guides D on either side of the frame, and a plurality of spaced longitudinal bars or fingers 4. The platforms are shown supported one from another by means of chains 20.

The loading platform comprises two sets of oppositely disposed longitudinal bars or fingers 6 and 7, respectively, mounted within the frame A so as to be capable of being swung upwardly upon a transverse horizontal axis by an ascending load upon the elevator. In the drawings the bars 6 comprising the set adjacent to the inclined carrier are shown secured at the end near the carrier to a transverse rock shaft 8 journaled in the sides of the frame A. This rock shaft has at one end a bent arm 9, which, by engagement with the arm 10 at one end of the front member 11 of the frame A, prevents the bars 6 from turning down under their own weight or that of a superimposed load. Upon the bent arm 9 is an adjustable counterweight 12.

The bars or fingers of each set, 6 and 7, respectively, are spaced apart from each other to allow the fingers 4 of the elevator platform to pass between them, while the bars 6 of one set are spaced apart from the alining bars 7 of the other set to allow the cross bar 3 of the elevator platform to pass between their adjacent ends. Upon all of these bars are preferably mounted rollers 13 in position to be engaged by the packages coming from the inclined carrier.

The side bars B of the inclined carrier are undercut at 14 near their inner ends so that they can be hooked over the front member 11 of the frame of the loading platform, and

are provided on their under sides with a cross bar 15, which forms a stop or rest for the oscillating tilting frame F. This frame, as here shown, comprises a plurality of 5 spaced longitudinal bars 16 supported upon cross straps or braces 17, and is pivoted at its forward or inner end to the side bars B of the carrier frame by means of pivot pins 18 which pass freely through the adjacent 10 bars 16 of the tilting frame. On the bars 16 are mounted rollers 19 which project slightly above the bars. Thus it will be seen that this tilting frame constitutes structurally and functionally a part of the gravity carrier itself, a structure upon which the packages are received and supported, but one which can be raised at its rear end so as to increase the pitch or incline of the discharge end of the carrier sufficiently to cause 15 the package upon it to move down to the loading platform. And by arranging the pivotal support of the tilting frame at its forward end this forward or discharge end will be maintained at all times at or just 20 above the level of the loading platform so that the packages need jump over no intervening gap between the carrier and the loading platform.

In order to arrest the travel of the boxes 30 G just before they reach the loading platform, a pair of oscillating bars or levers 21 are pivoted between their ends upon ears 22 depending from the cross bar 15. At their forward or inner ends the levers are formed 35 with upwardly extending retaining arms or hooks 23, which normally stand up above the end of the tilting frame in the path of the packages coming down the inclined carrier, as shown in Fig. 3. At their rear ends 40 these levers are pivotally connected by means of links 24 with the strap or brace 17 near the rear end of the tilting frame. Thus when the frame is tilted up on its pivots 18 at the front it will lift the rear ends of the 45 levers 21 and turn the retaining arms 23 down out of the path of descending packages, as shown in Fig. 4.

The frame F is tilted by means of a rock shaft 34 journaled in depending brackets 25 upon the side bars of the inclined carrier. To this rock shaft is keyed a pair of arms 26 which are pivotally connected with the frame by means of links 27. Upon the outer end of the rock shaft is a crank arm 28 55 which is pivotally connected by means of a link 29 with the lower end of a tripping lever 30 which is pivotally mounted upon a bracket 31 carried by one of the guides D of the elevator frame. This lever is mounted 60 so as to swing upon a transverse horizontal axis just within the guides D in position to be engaged and turned by the elevator platform E as it rises up above the loading platform, but out of the way of any load upon 65 the elevator. The link 29 is adjustable in

length by means of a turn-buckle 32, whereby the angle at which the lever 30 normally stands can be varied and adjusted so as to regulate the time and height at which the lever will be engaged by the ascending elevator platform.

In Figs. 5 to 8, inclusive, I have shown diagrammatically the operation of the loading devices and elevator at various stages in the operation. In Fig. 5 the tripping lever 75 and tilting frame are shown in normal position with the tilting frame resting upon its supporting bar 15 and the hooks 23 projected upward to form a retaining stop for the packages G coming down the carrier. The 80 upper elevator platform E is shown moving up with a package G' resting thereon. In this position the upper end of the tripping lever 30 extends across the path of the upper elevator platform E, which is just about to 85 engage it. It will be seen that the packages upon the inclined carrier have been held by the hooks 23 from moving forward onto the loading platform until the ascending box G' has been moved up out of the way. 90

When the upper elevator platform E has reached the position shown in Fig. 6 it will have engaged the lever 30 and turned it upon its pivot, thereby withdrawing the hooks 23 and tilting the tilting frame so that 95 the foremost box G is not only free to travel down onto the loading platform, but will be assisted in its descent by the tilting of the frame F. At this moment of time the upper elevator platform E will almost have 100 reached the upper end of the lever, while the elevator platform below will almost have reached the loading platform. It will be seen that the upper end of the tripping lever 30 has a slight inward curve, so that the 105 frame F will remain engaged by the elevator platform for an instant after it has been tilted and the hooks 23 have been withdrawn from the path of the packages, so as to allow time for the package G to run down 110 off the tilting frame before the lever is released.

In Fig. 7 the upper elevator platform is shown just moving past the end of the tripping lever 30 so as to release the lever, 115 while the foremost package G is just leaving the tilting frame and the lower elevator platform E is just reaching the loading platform to pick up the package.

In Fig. 8 the tripping lever 30 and the tilting frame F have been released and fallen back into their normal position shown in Fig. 5, while the lower elevator platform has picked up the package G and is carrying it up, and the retaining hooks 23 are 120 again in the path of the packages coming down the inclined carrier. Thus it will be seen that by the use of these devices the succeeding packages coming down the gravity carrier will be checked and held until the 125

5 foremost package has been picked up by the elevator and moved out of their way, and that the release and discharge of the package from the carrier to the elevator is automatically controlled and regulated by the engagement of the upper elevator platform with the tripping lever, and that the operation of these devices may be so timed as to bring about the transfer of each package, 10 to the loading platform coincidently with the arrival of another ascending elevator platform at any desired point.

15 It will be understood that by using the term "frame" for the package-tilting structure here shown and described, I do not mean to limit myself to the specific structure here shown nor to a "frame" technically so called but mean to include and cover any means for projecting the 20 packages from the carrier to the elevator which is within the principle of the invention, the scope of which is defined in the claims.

I claim as my invention:

25 1. The combination, with a gravity carrier and a straight lift elevator, of an auxiliary oscillating carrier section arranged at the discharge end of the carrier and having fulcrum support at its forward end, 30 said oscillating section resting normally in line with the carrier and adapted to receive packages therefrom, and means operatively connected with the oscillating section and actuated by the travel of the elevator for raising the oscillating section upon its fulcrum support coincidently with the arrival 35 of an elevator platform at a predetermined point.

40 2. The combination, with a gravity carrier and a straight lift elevator, of an auxiliary tilting carrier section arranged at the discharge end of the carrier and having fulcrum support at its forward end, said tilting section resting normally in line with the 45 carrier and adapted to receive packages therefrom, a package stop arranged at the forward end of the tilting section and standing normally in the path of descending packages, and means operatively connected 50 with the tilting section and stop and actuated by the travel of the elevator for raising the tilting section upon its fulcrum support at predetermined times and coincidently withdrawing the stop.

55 3. The combination, with a gravity carrier and a straight lift elevator, of an oscillating tilting section arranged at the discharge end of the carrier and forming a continuation thereof, rollers carried by said 60 tilting section, and means operatively connected with said tilting section and actuated by the travel of the elevator for tilting the tilting section at predetermined times.

65 4. The combination, with a gravity carrier having side bars, and a straight lift ele-

vator, of an oscillating tilting section arranged within the side bars of the carrier and pivotally supported thereon at the discharge end thereof, rollers carried by the tilting section and projecting above the side 70 rails of the carrier, and means operatively connected with the tilting section and actuated by the travel of the elevator for tilting the tilting section at predetermined times.

75 5. The combination, with a gravity carrier and a straight lift elevator, of an oscillating tilting section arranged at the discharge end of the carrier and resting normally within and upon the carrier frame, 80 said tilting section having fulcrum support at its forward end upon the carrier frame, rollers carried by said tilting section, a rock shaft arranged transversely of the tilting section and operatively connected therewith, 85 and means actuated by the travel of the elevator for turning the rock shaft and thereby tilting the tilting frame at predetermined times.

90 6. The combination with a gravity carrier and a straight lift elevator, of a package tilter arranged at the lower end of the carrier, rollers carried thereby, a package stop arranged at the forward end of the tilter, and means operatively connected with said tilter and stop and actuated by the travel of the elevator for withdrawing the stop and tilting the tilter coincidently with the arrival of an elevator platform at a predetermined point.

95 7. The combination with a gravity carrier and a straight lift elevator, of an oscillatory tilting section supported upon the carrier in position to receive packages therefrom, a package stop pivotally supported upon the carrier and operatively connected with said tilting section, said stop standing in the path of descending packages when the tilting section is in normal package receiving position, and means operatively connected with said device and actuated by the elevator in its travel for tilting said device at predetermined times, whereby the package stop is moved out of the path of the packages and the foremost package is projected into the path of the elevator.

100 8. The combination with a gravity carrier and a straight lift elevator, of a tilting device arranged at the discharge end of the carrier in position to receive packages therefrom, package detaining means pivotally supported upon the carrier and operatively connected with the tilting device, a pivotally mounted tripping lever standing normally in the path of the elevator, a rock shaft having link connection with the rear end of the tilting device, a crank arm keyed to the rock shaft and a link operatively connecting the tripping lever with said crank arm, whereby the tripping lever is 105 110 115 120 125 130

actuated by an ascending elevator to tilt the tilting device at predetermined times.

9. The combination with a gravity carrier and a straight lift elevator, of a tilting device arranged at the discharge end of the carrier and having rollers journaled therein, an oscillating bar having at the rear pivotal connection with said device and at the front a package retaining hook projected up above the rollers of said device; and means actuated by the upward travel of the elevator for tilting said device and thereby withdrawing said hook coincidently with the arrival of an ascending elevator platform at a predetermined point.

10. The combination with a gravity carrier and a straight lift elevator, of a tilting

device pivotally supported at the discharge end of the carrier, an oscillating package stop normally standing in front of the discharge end of the tilting device, and a lever operatively connected with said tilting device and package stop and actuated by the upward travel of the elevator to tilt said device and withdraw said package stop coincidently with the arrival of an elevator platform at a predetermined point.

In testimony whereof I affix my signature in presence of two witnesses.

CHARLES H. LISTER.
